UNITED STATES PATENT OFFICE.

GEORGE A. STANBERRY, OF TRADE, TENNESSEE.

NOSE-BAG.

1,181,808.

Specification of Letters Patent.

Patented May 2, 1916.

Application filed March 26, 1913, Serial No. 756,978. Renewed October 1, 1915. Serial No. 53,655.

To all whom it may concern:

Be it known that I, GEORGE A. STANBERRY, a citizen of the United States, residing at Trade, in the county of Johnson and State 5 of Tennessee, have invented new and useful Improvements in Nose-Bags, of which the following is a specification.

This invention relates to nose bags or feed bags, and it has for its object to provide 10 simple and improved means for supporting a feed bag of ordinary construction in such fashion that it may be readily adjusted to the proper or most desirable position relative to the mouth of the animal.

15 A further object of the invention is to provide simple and improved supporting means of a nature which when the animal stretches its neck in reaching for the food will have a tendency to draw the bag upward toward 20 the mouth, while when the food is being masticated there will be a tendency for the bag to drop, leaving the animal free and ample space to chew the food.

25 A further object of the invention is to simplify and improve the construction of the supporting plates and the pulleys associated therewith.

With these and other ends in view which 30 will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention, it being, however, understood that no limitation is necessarily made to the precise structural details therein exhibited, 40 but that changes, alterations and modifications within the scope of the claims may be resorted to when desired.

In the drawings,—Figure 1 is a perspective view showing the head and neck of an 45 animal to which a nose bag having the improved supporting means has been applied. Fig. 2 is a vertical longitudinal sectional view of the device removed from the head of the animal. Fig. 3 is a sectional view, enlarged, taken on the line 3—3 in Fig. 2. Fig. 50 4 is a sectional detail view taken on the line 4—4 in Fig. 2. Fig. 5 is a perspective detail view showing one of the supporting members and related parts, detached and separated.

Corresponding parts in the several figures 55 are denoted by like characters of reference.

The nose bag B which is of ordinary construction is provided adjacent to its upper edge and at diametrically opposite sides with reinforcing loops or straps 10 of leather 60 or other suitable material, said loops or straps serving for the attachment of buckles 11. Adjustably connected with said buckles are the ends of the head strap 12 which passes over the head of the animal back of 65 the ears and which serve to support the weight of the nose bag and its contents.

C, C represent supporting plates or disks, each of said disks being provided with a slot 13 with which a strap 14 carrying a buckle 70 15 is connected. The cheek portions of the strap 12 engage the buckles 15 which are adjustably connected therewith, thereby suspending the disk C adjustably on said cheek straps. The disks C are provided with additional slots 16 for the passage of a strap 17 having a buckle 18, whereby said strap which passes across the nose of the animal may be lengthened or shortened to fit the device comfortably on the head of the animal. 80

Each of the disks C supports on the outer face thereof a keeper 19, the same being secured by means of a bolt 20 having a non-circular head 21 which is countersunk in the outer face of said keeper. The bolt 20 passes 85 through the disk C and is secured by a nut 22 which is countersunk in the inner face of the disk. The bolt 20 supports intermediate the keeper 19 and the outer face of the disk a grooved pulley 23 and washers 24 that lie 90 intermediate the ends of the pulley and the inner face of the keeper and the outer face of the disk, respectively, said washers being shaped to abut on the ends of the keeper so as to be held against rotation. These washers 95 may be readily replaced by new ones when worn, the parts being readily disassembled by simply loosening the nut on the bolt. Guided over the pulleys 23 are the ends of a strap 25, the looped portion of which may 100 be connected with the cheek hook 26 when the device is in use; the terminals of the strap 25 are connected adjustably with the buckles 11, being provided with a series of apertures 25' for such adjustment. 105

As will be seen from the foregoing description, taken in connection with the drawings hereto annexed, the weight of the nose

bag is supported by the head strap 12 which passes over the head of the animal. Said head strap being connected adjustably with the nose bag by means of the buckles 11, it follows that the bag may be readily adjusted to fit the heads of animals of different sizes. In like manner the supporting plates or disks C, as well as the nose strap 17, may be adjusted; the said supporting plates or disks 10 being suspended from the cheek portions of the head strap by the straps 14 and buckles 15. The nose bag being, furthermore, connected with the check hook 26 by means of the strap 25 passing over the pulleys 23, it follows that when the animal stretches its neck in reaching for food, the nose bag will be elevated or brought close to the mouth of the animal, after which, while the animal 15 is masticating the food, the nose bag is permitted to drop to a position where its contents will not obstruct the mouth and interfere with proper breathing and mastication. The supporting members or disks C are provided on their inner faces with flat smooth 20 keepers 27 which are located about diametrically opposite to the slots 13 for the passage of the cheek portions of the strap 12, thereby causing the supporting plates or disks to be held on the cheek straps with 25 sufficient firmness to insure the perfect operation of the device.

The construction of the improved device is extremely simple and inexpensive, involving with the exception of the supporting plates having the keepers and pulleys the use of no fittings that are not standard and procurable in the open market. The supporting plates and related parts are ex- 30

tremely simple and of such a nature as to be readily disassembled for convenience in 40 making repairs when worn.

Having thus described the invention, what is claimed as new, is:—

1. In a device of the class described, a pair of supporting members consisting of 45 disks having pulleys journaled adjacent to their outer faces and provided with flat smooth keepers on their inner faces, a nose strap connecting the disks, a head strap having cheek portions guided through the 50 flat smooth keepers, means connecting the cheek portions with the disks, a nose bag having buckles with which the cheek portions of the head strap are connected, and a check strap guided over the pulleys on the 55 disks and connected terminally with the buckles of the nose bag.

2. A pair of supporting members consisting of disks, each having a buckle carrying strap connected therewith, a nose strap connecting the disks, a guide pulley and a keeper on the opposite sides of each disk, a nose bag, a head strap having cheek members adjustably connected with the buckles, said cheek pieces being guided through the 60 keepers on the disks and terminally connected with the nose bag, and a check strap guided over the pulleys and connected terminally with the nose bag.

In testimony whereof I affix my signature 70 in presence of two witnesses.

GEORGE A. STANBERY.

Witnesses:

COLUMBUS F. MAY,
GEORGE M. LOVE.
